AUTOMATIC REEL FOR PAPER ROLLS

Henry A. Wise Wood, New York, N. Y., assignor to
 Wood Newspaper Machinery Corporation, New
 York, N. Y., a corporation of Virginia

Application August 17, 1932, Serial No. 629,105
 Renewed April 3, 1937

2 Claims. (Cl. 242—64)

This invention relates to means for supporting a plurality of paper rolls for feeding a printing press and particularly to a reel wherein the fresh roll is spliced from the running roll without stopping the press.

The principal objects of this invention are to provide a reel of such a construction as to enable it to carry the heavy rolls, which often are not entirely concentric, and to enable those rolls to run at a high speed without unduly vibrating the structure; to provide means by which the supports for the ends of the reel will be tied together to add to the firmness of both; to so construct the reel as to obviate the necessity of an additional bed plate construction, which is necessitated with the usual type of reel when the main shaft is supported on pedestals; and to construct it to be used in connection with very simple tension members.

Other objects and advantages of the invention will appear hereinafter.

Reference is to be had to the accompanying drawings, in which

Fig. 1 is an end view of a reel constructed in accordance with this invention;

Fig. 2 is a front elevation of the same as indicated by the arrow 2 in Fig. 1;

Fig. 3 is an enlarged front view of certain parts shown in Fig. 1;

Fig. 4 is a sectional view on the line 4—4 of Fig. 3;

Fig. 5 is a similar view showing the other end of the reel shaft;

Fig. 6 is an end elevation of the parts for operating the split nut;

Fig. 7 is a sectional view on the line 7—7 of Fig. 6;

Fig. 8 is a sectional view of the split nut on the line 8—8 of Fig. 7;

Fig. 9 is a plan of the double cam for operating the split nut;

Fig. 10 is an end view of the spindle bearing looking in the direction of the arrow 10 in Fig. 2;

Fig. 11 is a sectional view thereof on the line 11—11 of Fig. 10;

Fig. 12 is an elevation of the opposite spindle bearing looking in the direction of the arrow 12 in Fig. 2;

Fig. 13 is a sectional view of the same on the line 13—13 of Fig. 12;

Fig. 14 is an elevation of the reel contact holding mechanism;

Fig. 15 is a sectional view of the same on the line 15—15;

Fig. 16 is a sectional view of the limit switch and associated parts;

Fig. 17 is an elevation of the same as indicated by the arrow 17 in Fig. 16.

Referring to Figs. 1, 3, 4 and 5, it will be seen that the columns 1 of the printing press frame provide supports for the apparatus. These supports carry a pair of capped end brackets 2 constituting a rigid structure for supporting the parts and constituting a tie at each end of the 10 device between the columns which support it. By supporting the reel in this way a very sturdy construction is obtained and the reel can be supported high enough so as to leave a space under it. The end brackets 2 provide supports for 15 rotatable bearing boxes 4 and 5 at the opposite ends of the main shaft 6, which is concentrically supported and fixed to rotate with said boxes by means of dowel pins 7.

The shaft 6 carries a key 17 extending the full 20 length between the bearing boxes 4 and 5 and held in by screws 18 thereby providing a spline arrangement for the two spiders 16 which are carried by the shaft 6. The key 17 holds the spiders in alignment but permits end motion, which is 25 imparted to the spiders by the rotation of the register screw to be described.

For the purpose of rotating the reel, a motor 32 is provided secured to a casing 33, preferably integral with the end bracket 2. On the shaft 30 of the motor is a pinion 34 operating a gear 35 on a shaft 33 mounted in ball bearings 28 carried by the casing 33. On this shaft is a worm 27 driving a worm wheel 26. The worm wheel 26 is secured to and rotates with an end plate 21.

The bearing boxes 4 and 5 also provide a rotatable mounting for a side register screw 9, which is carried at both ends in ball bearings 19. One end of the register screw 9 is provided with a space collar 11 and a lock nut 12 and the other end carries a gear 13 keyed to the screw and held in place by a lock nut 14.

This register screw is rotated by a motor 23 on a bracket 24 supported by a connection plate 25 which is concentrically secured to the end plate 21 comprising a part of the bearing box 4 on one side. Thus the motor rotates bodily with that bearing box. The shaft of the motor is provided with a pinion 22 meshing with a gear 19 to which is secured a pinion 18 meshing with the gear 13 fixed to side register screw. It will be obvious therefore that any operation of the motor will cause the side register screw to rotate in one direction or the other, thereby moving the 55

two spiders 16 back and forth as needed, if both spiders are connected. Figs. 6 to 9 show the manner of connecting and disconnecting the side register screw 9 with respect to the spiders 16. The bracket 10 is secured to spider 16 and provides a rotatable mounting for a shaft 71, one end of which carries a double pathed cam 72 and to the other end of which is clamped an arm 73. The free end of the arm 73 carries a handle 74 having a spring-pressed retractable dowel pin 75 adapted to fit in a hole in the spider 16. Two studs 76 secured to split nuts 77 fit in the two cam paths in the cam 72. Therefore the oscillation of the cam 72 separates the split nuts 77 or brings them together on the screw part of the side register screw 9. These features are duplicated on the other end of the machine so that both split nuts can be connected with the screw 9 or either of them as desired. They are closed together whenever the dowel pin 75 is located in its hole in the spider and in that position the rotation of the side register screw 9 will move the spiders along the shaft 6. In this manner any position of the spiders may be obtained by leaving either one of the dowel pins 75 in its hole and rotating the side register screw. Both of the spiders can be moved along in the same direction for side register by leaving them both connected. This is a useful feature as it occurs some times that a fractional width roll on one side of the press for one edition has to be run on the other side of the press for the next edition. Heretofore in such a case it has been necessary to strip the reel of all rolls, move the two spiders individually and reload the reel. With my construction, however, it is only necessary to press a button and the motor 23 will operate to move the roll-filled reel from one side of the machine to the other with practically no loss of time and no effort.

In the construction shown, covers 78 and 79 on each of the three spindles and a center cover 80 are provided on one spider, which is adapted for a web splicing device. These covers can be made removable or made integral parts of the spider 16.

As the side register motor 23 rotates with the reel it is necessary to use selector rings for distributing electric power properly. This is done by employing an insulation ring 37 secured to the plate 25. This insulating ring has contact rings 38, five being shown but usually only two or three are used. Carbon brushes 39 bear against these rings 38 with spring pressure produced by springs 40. A cap 41 is used to back up the whole device and this cap is mounted in a sleeve 42 of bakelite or other insulating moldable material. A wire may be attached for supplying electric power through the brushes 39 to the contact rings 38 and thus to the motor 23 by means of a connection 43. This connection is soldered to a sleeve 44 to provide the necessary connection.

One spider is provided with movable chucks 58 to permit the mounting of the web rolls. This is arranged for by providing, in axial alignment with each chuck, a shaft 49 inside a cylinder 48, this shaft and cylinder telescoping together. A cylinder 48 is mounted slidably in each arm of the spider and held against rotation by a dowel screw 60 fitting in a slot 51 in the cylinder. A rack 52 is secured to the cylinder 48. This is actuated by a shaft 53 operated by hand by an arm 54 thereon. This arm is provided with a handle 55, which carries a retractable dowel 56

fitting in a hole in the side of the chuck to hold the chuck in place when the paper roll is locked up. On the shaft 53 is a pinion 52* adapted to move the cylinder 48, and therefore the chuck, back and forth.

The shaft 49 carries a mounting for ball bearings 57 and the ball bearing supports the chuck, which is held in place by a sealing plate 59 secured to the chuck. The tapered end of the chuck 58 is so constructed as to fit in the paper core 10 of the roll and thereby provides a support for one end. The shaft 49 is longitudinally adjustable by means of an adjusting screw stud 60, the inner end of which is threaded into the end of the shaft 49 and to the outer end of which is fixed a hand wheel 61 for adjusting it. There is a recess in a cover plate 62 fixed to the end of the cylinder 48 in which recess is located a shoulder on the screw stud 60 to hold it against end motion.

On the other end of the machine the spindle bearing for the roll comprises a shaft 63 on which is secured the complementary chuck 64 for the same web roll. The shaft is carried in ball bearings 65, being held in place against the shoulder 25 on the shaft by spacers 67 and 68 and a lock nut 69. The particular construction of parts at this end is adapted for installation with the parts of an automatic pasting machine, particularly for the automatic paster, which is the subject matter 30 of my prior Patent No. 1,843,469.

It will be understood that a simple reel could be made not particularly adapted for use with this automatic machine in a less elaborate manner.

Referring to Figs. 16 and 17 a limit switch construction is shown, which prevents the spider from being jammed against the bearing box at the end. This is shown in the form of a shoe 81 guided in an upright position by a bracket 82 secured to the end bracket. This shoe is pinned to a switch rod 83 which is spring-pressed and has its bearing in the bracket 82 and also in the end bracket. The switch rod 83 is provided with a collar 84 against which the spring presses and it bears against a roller 85 on an arm on the shaft of the limit switch 86.

It will be seen that the switch rod 83 is spring-pressed to the right in the position shown until the cover plate 80 of the spider bears against the upper part of the shoe 81 which opens the switch 86 and disconnects the power automatically from the motor 23. A similar switch construction is used on the other end of the reel, as shown in dotted lines in Fig. 2.

The motor 23 is reversible and of course, these switches operate to stop the motion of the spider longitudinally of the shaft, only in one direction in each case: that is, the direction in which they move. This arrangement is provided, of course, 60 to prevent damage. It is possible to move the spider or spiders in the opposite direction away from the limit switch as is customary with limit switches of this kind.

In connection with this auto reel simple tension members 87 are employed in the form of straps. The lower ends of these straps are detachably mounted by hooks 88 latching over a shaft 89 secured by brackets 90 to the foundation or floor. The other ends of the straps are secured to the ends of individual levers 91, which are pivotally mounted on the frame of the machine and carry rods 92 at their other ends for the support of a series of removable weights 93. Four tension members are shown as it is con- 75

venient to unlatch one each for each page width of narrowing of the paper when fractional width rolls are used. When a half width roll is used, two tension straps are used, for a three-quarter roll, three of them are used. They are very easily thrown out of operation by unlatching the hook 89 and hanging the belt up over a pipe 94 which extends across the reel and is mounted on the columns 4.

10 It will be seen that a rotatable paper roll-supporting device is provided which is sturdy in construction, particularly on account of the brackets 2, uses little or no floor room because it is mounted on the columns of the press, within 15 the boundaries thereof, carries disconnectible means for moving the spider longitudinally on the reel shaft by power and constructed to be used in connection with very simple tension members which can be put out of operation and brought 20 back into operative position very easily and quickly. Furthermore, it can be located high enough in the machine so as to leave a clear floor space underneath the reel for cleaning and repairing.

25 The details of the spider shifting device, that is, the double nut and two path cam arrangement, constitute the subject matter of my previous Patent No. 1,957,122, filed May 12, 1932, patented May 1, 1934, and is claimed herein only in 30 combination with the other features.

Although I have illustrated and described only one form of the invention I am aware of the fact that modifications can be made therein by

any person skilled in the art without departing from the scope of the invention as expressed in the claims. Therefore I do not wish to be limited in this respect otherwise than as set forth in the claims, but what I claim is:—

5 1. In a web roll supporting reel, the combination of a frame having bearings, bearing boxes rotatably mounted in said bearings, a shaft extending from one bearing to the other, spiders on the shaft constituting a web roll support, 10 means for fixing the shaft to the two bearing boxes so that they will rotate together, one of the bearing boxes having a worm gear thereon, a motor carried by the frame, means operated by the motor for turning the worm gear for rotating 15 the reel, an end bracket fixed with respect to said worm wheel, a motor carried by the end bracket concentrically with the shaft, and means operated by the second motor for shifting the spiders along the shaft.

20 2. In a web supply device, the combination of a frame, a shaft carried thereby, two spiders keyed to the shaft and movable therealong and constituting a roll supporting reel, bearing boxes on the frame to which said shaft is fixed, one of them 25 having an end plate by which the box and shaft can be rotated, an adjusting screw carried by said boxes and adapted to be connected with the spiders for adjusting them, a gear fixed on the screw, a bracket carried by said end plate, a motor carried by the bracket, and means for rotating said gear from the motor.

HENRY A. WISE WOOD.
